YARN PACKAGING DEVICE

William J. Elvin, Cumberland, Md., and Joseph L. Killoran, Drummondville, Quebec, Canada, assignors to Celanese Corporation of America, a corporation of Delaware

Application August 30, 1934, Serial No. 742,108

2 Claims. (Cl. 117—25)

This invention relates to a yarn packaging device and more particularly to such a device that draws yarns from a package such as a bobbin, imparts a twist to the yarn and winds the same into a cross-wound package such as a cheese. This invention also relates to a tube holder for holding the core, about which a package is wound, positively in position yet adapted for quick removal and replacement.

10 An object of the invention is a commercially practical device which will twist and package fine filaments of yarns such that the resulting package may be large say, 1½ lbs., firm, free from tendencies to fluff at the ends and which is uniform in tension, without soft spots.

15 Another object of the invention is a commercially practical device which will twist and package fine filaments or yarns, that is automatic in response to failure of yarn or filament and one in which the yarns and filaments may be threaded quickly and full packages removed and empty cores inserted without disturbing the operation of the adjacent and/or companion elements, packages, etc. of the device.

20 Another object of the invention is a device so designed that the package formed thereon is uniform throughout. Other objects of the invention will appear from the following detailed description and drawings.

25 In the drawings wherein like numbers refer to the same or equivalent elements:

Fig. 1 is a perspective side elevation of a device, constructed according to this invention, with obvious frame and bearing members omitted.

30 Fig. 2 is an enlarged side elevation partially in section of the package lifting elements and core holding elements shown in Fig. 1.

Fig. 3 is an end view of the package lifting elements shown in Fig. 2.

35 Fig. 4 is a detail, partially in section of a part of the core holding device.

Fig. 5 is an end view of the core holding device shown in Fig. 4.

40 Fig. 6 is a perspective side elevation of a part of the device shown in Fig. 1 having a modified form of drive for the yarn guiding means.

Fig. 7 is a side elevation in detail of the drive mechanism shown in Fig. 6.

45 Fig. 8 is an end view partially in section taken on the line 8—8 of Fig. 7 of a part of the drive mechanism.

50 In the commercial twisting and packaging of yarn, devices are built to twist and wind a plurality of yarns simultaneously so that power and floor space may be conserved and so that one

operator may tend to the winding of a large number of packages. In such devices exhaustion of feed bobbins and breaks may occur, along a machine operated by one operator, faster than they can be refilled or spliced. In such an event 5 the take-up package being formed is rotated without tension on the free end of the yarn which causes a loosening of the outer wrappings of the package. If a yarn breaks the same difficulty is found on the package being formed. 10 Moreover in starting up the device, since both hands of the operator are required to set the yarn stop device and feed the yarn into the guide, it is impossible for him to keep the feed bobbin spindle away from the driving belt so as 15 to stop its rotation with the result that too much twist is imparted to the yarn and it tends to break.

These difficulties are overcome by this invention in that the device is responsive to the failure of 20 the yarn removing the forming package from the source of power which causes it to rotate. It also throws the bobbin out of driving relationship with the source of power that causes it to rotate and applies a brake to same to bring it to a quick 25 stop. Both the feed package or bobbin and the take-up or forming package are moved from operative to inoperative position without affecting the other similar units of the device. While thus in the inoperative position a new supply of 30 yarn may be made or the failure of the yarn corrected without interfering with the device as a whole and after correction the elements may again be thrown into operative positions.

35 In the cross-winding of packages, such as cheeses, the yarn is guided to the take-up package by means of a reciprocating guide member. This guide member reciprocating transversely to the direction of rotation of the take-up package directs the yarn or thread onto the package in a 40 spiral from one end to the other and back. If the rate of reciprocation is constant relative to the rate of rotation the point of reverse of the yarn will fall in ever so many cycles on the point of reverse of a former laid increment of yarn. In this manner a cross-wound package is formed the ends of which are not uniformly solid but contain hard spots where the points of reverse of the 45 yarn are one above the other and soft spots where the points of reverse of the yarn 50 are not to be found. Some packages, depending upon the ratio of the traverse to the revolution of the yarn, may contain the points of reverse in lines radiating from the center making a package very easily fluffed, i. e. increments of 55

yarn forming arcs across the end of the package. These types of packages cannot be roughly handled nor even employed in certain types of textile operations.

5 In employing the device forming this invention, however, the ratio of the reciprocation of the guide means is not constant in respect to the rate of rotation of the take-up package and therefore the points of reverse do not fall in 10 limited areas on the end of the package but are evenly distributed throughout the area. This forms a solid package that may be shipped or otherwise handled and applicable to textile operations without fluffing at the ends. This is accomplished not by progressive change in the ratio referred to which would lead to the same fault as a constant ratio but by varying the ratio first to one side and then the other of a mean ratio.

15 In accordance with our invention we have devised a method and device for accomplishing the same that twists yarns and crosswinds them to a package which is solid and free from ununiform ends, and which device is responsive to the failure of yarn to prevent tangling of the yarn or 20 loosening of the package. Two modifications of such a device are here shown and described in detail.

25 In the drawings, with particular reference to the modification shown in Fig. 1, a motor 1 is used as a source of power imparting rotation to the pulley 2. The motor is mounted on a car or movable platform 3, which may be moved in a direction parallel to the length of the machine along supporting rails 4. The car or platform 30 may ride on wheels or rolls to reduce friction. The platform 3 has teeth cast onto or cut into it on each side to mesh with a gear 5. Gear 5 and lever arm 7 are directly connected to a shaft 6, suitably journaled in a bearing on the frame 35 trackway 4, and lever arm 7 is connected to a counterweight 8, said counterweight being shown as integral with lever arm 7 but, if desired, may be adjustable along lever arm 7. In place of an electric motor, as shown, other sources of power 40 may be employed and corresponding belt tighteners adapted therefor. With the arrangement shown, any slack that may occur in the belt 9 is automatically taken up due to the force or pressure exerted by the counterweight 8 readjusting 45 the position of the motor 1 and the pulley 2. In place of the vertical motor a horizontal motor and appropriate gears may be mounted on the platform to accomplish the same result.

50 Pulley 2 drives belt 9, which may be supported 55 in position by idler pulleys 10 and 11 spaced along either or both sides of the machine. The belt 9 drives pulley 12 and also a plurality or series of bobbin spindles 13, that may be spaced along either or preferably both sides of the belt run.

60 Bobbin spindles 13 may be pivotally mounted each on an arm 14, which may be pivoted in a tension spring pivot to a bracket 16. The tension spring may be mounted inside the housing 15 and fastened to 15 and also fastened to bracket 65 16, in such a manner that the bobbin spindle is forced toward a position so that it would be in driving relation to the belt 9. The bobbin spindle may have a guide for the belt formed by the flange 17.

70 The desired twist may be given to the yarn 18 by causing the bobbin spindle 13 and the bobbins 61 carried thereby to rotate at a greater rate than the yarn is drawn from the bobbin. The yarn is drawn through eyelets or guides 19 and cleaner 20 across a bar 99 and reciprocating thread guide

75 21 onto the take-up package 22 which is held in place by an expanding tube or core holder 100, more completely shown in Figs. 2, 3, 4 and 5, and which is driven by friction rolls 23. All parts contacting the yarn such as guides, eyelets, bars, etc. may be enameled or chromium plated or otherwise treated to furnish a smooth true surface that is not injurious to the filaments of the yarn. The friction rolls 23 may be covered with cork, compositions, etc. or they may be formed of wood, etc.

80 The pulley 12, driven by belt 9, may be directly fastened to shaft 24, which drives worm or bevel gears 25 and 26 that in turn drive shaft 27. Shaft 27 may be fastened to a gear 28 which drives gears 29 and 30. Each gear 29 and 30 is connected to a shaft 31 and 32 respectively, which have mounted thereon at spaced intervals a plurality of friction rollers 23 faced with cork or other composition. The friction drive for the 85 take-up package insures a constant speed of the periphery of the package and thus a constant feed rate of thread being applied thereto. There may be one friction roller for taking care of five or 90 six spindles according to the spacing of the supporting frames, which are not shown in detail on the drawings. The rollers 23 may be solid or hollow metal rolls supported by hubs and spokes and are suitably locked to the shafts 31 and 32.

95 The shaft 31 is also directly fastened to a gear 34 which drives gear 35. Gear 35 and bushing 36 are directly fastened to shaft 37 that may be suitably journaled in the main frame, not shown. Bushing 36 is bored eccentrically and rotates inside a bearing on a lever 38. In place of the 100 eccentrically pivoted bushing, a crank or other suitable element may be employed to give a reciprocating movement to the arm 38. The arm 38 is pivoted on a pin 39 which is adjustable in a slot 42 of a lever 40 and lever 40 is positively fastened to a shaft 41.

105 Bushing 36 being bored eccentrically and rotating inside an arm 38 imparts a back-and-forth motion to the arm 38 through the center line of shaft 37 and center line of pivot pin 39 imparting to lever arm 40 and shaft 41 a rocking motion governed by the movement of arm 38. The shaft 41 may be suitably journaled in bearings in the main frame, not shown.

110 Arm 42 may be directly fastened to shaft 41 by means of keys or other suitable means. Thus arm 42 will be given the same rocking motion as lever arm 40. A rod 43, such as a steel wire, is pivotally connected to arm 42 and is adapted to ride back and forth, its outer end carried by a drop wire 44. The drop wire 44 may be suitably pivoted on a pin 97 which is securely fastened to bracket 98 attached to a part of the main frame. Drop wire 44 is held in a raised position by thread 18 as long as yarn is being taken up on tube 22. As soon as there is a failure of thread, drop wire 44 swings out and down, since it is so pivoted on the pin 97. The drop wire 44 drops out past or beyond the line of travel of the thread 18 when the thread is passing through the eyelets 19 and cleaner 20. The drop wire 44 pivoted on pin 97 in dropping down changes the position, or raises the projecting end of the wire, and since rod 43 is supported by this projecting end, also changes the position of or raises said rod 43.

115 Suitably fastened to the main frame is a housing 46. The housing 46 contains a trigger 48 directly fastened to a catch 47. The trigger 48 and catch 47 are forced into operative position

by a spring 49 resting on the trigger and the rear of the housing 46.

In operation, when the rod 43 is in a down position as shown, or equivalently when the yarn is being taken up on tube 22, the lug 45, which is adjustably fastened to rod 43, passes back and forth under trigger 48 and does not come in contact therewith, but when the thread breaks or there is a failure of thread allowing wire 44 to drop down, raising its projecting end and thus raising rod 43, lug 45 then comes directly in line with trigger 48 and contacts therewith. Due to the motion of arm 42, said motion being imparted to lug 45, the lug having a flat rear abutment 10 head contacts with trigger 48 pushing it back against the spring 49 and drawing the catch 47 into inoperative position from the seat on collar 115.

A collar 115 is directly fastened to a lifting rod 20 50. When catch 47 is drawn to its inoperative position from its seat on collar 115 it allows the lifting rod 50 to be forced upward by the action of a spring 51 which is under compression while catch 47 and collar 115 are coacting. Suitably positioned on the main frame is a bracket 62 that acts as a guide for the lifting rod 50 and as a bearing for the spring 51.

The upper end of lifting rod 50 at 52 is made suitable to engage a bracket 53 which carries tube 30 22. The bracket 53 is adapted to pivot about a stationary rod 54 or other suitable means. Thus as lifting rod 50 is released from catch 47 and raised by spring 51, it engages at 52 the bracket 53 swinging it up and about rod 54 lifting there-with the package 55 on the tube 22 from the friction roll 23, stopping the rotation of the package. The bracket 53 has a split bearing formed by the arms 57 controlled by a screw 56, for decreasing or increasing the bearing pressure on rod 54. Thus the amount of throw of bracket 53 may be 40 regulated so that it prevents jumping of the core holder with the package thereon and yet is not sufficiently tight to prevent free movement thereof.

A cam 58 is directly fastened to lifting rod 50 and suitable means provided for adjusting the height of same in respect to other elements of the device. As lifting rod 50 is raised up cam 58 is also raised and engages with an arm 59, that may be a part or extension of lever arm 14, pushing it back and about 15 as a pivot. Arm 59, pivot housing 15 and arm 14 are integral, or adapted to function as such, and move as a single unit so that as cam 58 pushes arm 59 back and about pivot 15, arm 14 is moved away from the device, causing spindle 13 to be relieved of contact with belt 9. A stationary arm and brake member 60 are suitably attached to, or made integral with, bracket 16 that may be attached to bracket 62. As the arm 14 is rotated forward by cam 58, the whorl of spindle 13 is jammed against brake member 60 that may be lined with a suitable brake lining. The pivot housing 15 contains a coil spring fastened to the housing and the pivot rod of arm 16, that tends to force the spindle 13 against the belt 9. The brackets 62 and 16 may be fastened to the main frame in any suitable manner as by rods 116 and 117 in such a manner they may be accurately positioned in respect to other elements of the device.

The lifting rod 50 is equipped with a pedal 63 that may be worked by the foot of the operator. In operation, in order to reseat catch 47 and collar 115, foot pedal 63 is stepped on after the failure of the thread has been corrected and drop

wire 44 has been placed back of the thread. Wire 43 is then lowered due to the projecting end of wire 44 being lowered and thus lug 45 passes along underneath and out of contact with trigger 48. Catch 47 rides on collar 115 until collar 115 5 has been lowered by means of pressing down on foot pedal 63 to a position where catch 47 reseats on top of collar 115, being forced in place by spring 49 contained in housing 46. When foot pedal 63 is stepped on, cam 58 is lowered allowing 10 arm 59 to move forward and arm 14 backward to engage spindle 13 with belt 9.

For guiding the thread onto the take-up package 55 there is provided a reciprocating guide member 21 that causes a cross-winding of the 15 thread upon the package. It is desirable that the reciprocation and thus the laying on of the thread upon the package have a mean speed relative to the peripheral speed of the take-up package yet a speed that varies to either side of the mean 20 speed such that the points of reverse of the thread upon the package will not fall with too great a frequency upon the same or about the same axial line causing a package that has an ununiform end. This may be accomplished by the driving 25 means for the cam that governs the reciprocation of guide 21.

One method of varying the speed of reciprocation of the guide 21 is shown in Fig. 1 of the drawings to which particular reference is directed. 30 On shaft 31—33 is a sprocket wheel 64 suitably fastened thereto. A shaft 67 suitably journaled in the main frame has fastened thereto a sprocket wheel 65 that is driven from sprocket wheel 64 by a drive chain 66 which is preferably a roller 35 drive chain. Sprocket wheel 65 gives rotation to shaft 67 that has fastened thereto a cone pulley 68 and a gear 69. Cone pulley 68 drives a cone pulley 71 through a belt 70. The cone pulley 71 is suitably fastened to a shaft 73 journaled in the 40 main frame, which shaft has mounted thereon a sprocket wheel 72.

On a shaft 76 suitably journaled on the main frame are gears 74 and 75 while on a shaft 79 also journaled in the main frame is a gear 77 and a 45 cam 78 having a camway 81. Gears 69, 74, 75, and 77 form a speed reducing mechanism carrying power from shaft 67 to cam 78 which may be replaced by any suitable speed reducing device.

A pin with a roller 80 engages the cam groove 50 81 of the cam wheel 78. The pin with roller 80 is fastened to a rod 82 suitably mounted for sliding movement which rod has a block 83 fastened thereto carrying a belt guide 84. Upon rotation of the friction rolls and shaft 31 there is set up, 55 through shaft 67 and the speed reducing mechanism a rotation of cam wheel 78 that imparts a reciprocatory movement to belt guide 84 that in turn moves the belt 70 back and forth across the cone pulleys thus giving a variable speed to shaft 60 73. The cone pulley 68 and cone pulley 71 may be of the same size, but preferably the large end or greater diameter of one is put opposite the smaller end or lesser diameter of the other thus effecting a variable speed of rotation of the driven 65 pulley 71 and the sprocket wheel 72 attached to its shaft.

Suitably journaled in the main frame is a shaft 88 having fastened thereto a sprocket wheel 85, registering with sprocket wheel 72, and a drum 70 cam 87 having camways 92 and 93. Sprocket wheel 85 is driven from sprocket wheel 72 by means of a sprocket chain 86. In this way the variable speed of cone pulley 71 is imparted to drum cam 87. The barrel 81 of the drum cam 75

has two grooves 92 and 93 cut in it at an angle of 90°, or other suitable angle, to each other, and these grooves coat with pins and rollers as at 91 that are suitably fastened in a slide head 90. 5 In a device having spindles along both sides it is preferable to have a slide head with its accompanying parts for each side, one side operating in groove 93 while the other side operates in groove 92.

10 The slide head 90 may be guided in its variable reciprocating movement by a slotted groove 94 in the drum cam housing 95. The slide head, through adjustable bar 96, is connected to a rod 89, preferably square in cross section, that is supported and guided at suitable intervals from the main frame. The rod 89 is connected to a plurality of thread guides 21. There is one thread guide provided for each set of spindle and take-up package. The thread guides are automatic 15 and thread themselves and they guide the thread as it is wound upon the take-up package 55.

The reciprocatory motion of the thread guides is derived from the shaft 31 through the cone pulleys and reciprocating cone drive belt 70. Thus 25 there is imparted to the thread guides 21 a variable reciprocation having a mean speed derived from the cone pulleys when the belt 70 is at their centers and a maximum and minimum speed when the belt 70 is nearer the ends of the cones. 30 As the speed of reciprocation of the belt 70 is at a reduced speed relative to that of the cones, a variable reciprocatory motion is imparted to the guides 21 such that the points of reverse of the threads are well distributed about the end of the 35 take-up package.

In operation the machine is started and assuming the devices have all been in operation the starting operation for any one of the plurality of units on the machine is as follows; first considering the position of the various parts of the unit 40 before it is started.

Drop wire 44 is in the down position, there being no thread 18 passing from eyelet 19 to automatic thread guide 21. Rod 43 is raised because 45 its supporting point on the projecting end of wire 44 in pivoting about pin 97 has raised. Lifting rod 50 is at the top of its stroke since catch 47 has been drawn back releasing collar 115. Bracket 53 is raised by lifting rod 50, and take-up 50 package 55 is disengaged from cork roll 23. Spindle 13 is disengaged from belt 9 and rests against brake 60.

The loaded bobbin 61 of the yarn desired to be 55 twisted, or further twisted, is placed on spindle 13. The yarn from the bobbin is threaded through eyelets 19 and thread cleaner 20 and then by a suitable operation, fastened to tube 22 on expanding tube holder 110. The machine is running constantly, there being no need to shut it down in 60 order to start a unit. The operator then holds the slack out of the yarn by drawing the yarn down across bar 99. Then upon stepping on foot pedal 63, take-up package 55 is let down to engage friction roll 23 and spindle 13 is released from stop 65 60 by lowering of cam 58 and put in driving contact with belt 9 due to the spring in pivot housing 15. As the yarn is taken up on package 55 which rotates due to friction with roll 23, automatic thread guide 21 is in its variable reciprocating 70 motion, and due to its self threading construction, picks up yarn or thread 18 and builds the yarn into a firm, self-supporting, cross-wound package, such as a cheese, on the tube; the variable reciprocation of the guide 21 being sufficiently 75 rapid to form a solid cross-wound package.

The term yarn and thread are here used as substantially synonymous and may include fibers or filaments of any suitable materials such as filaments of organic derivatives of cellulose, regenerated or reconstituted cellulose, silk or mixtures of these or the yarns may be formed of fibers twisted or otherwise held together of cotton, wool, flax and the like. 5

By reason of the automatic take-up package lifter, which disconnects the applied power that 10 causes rotation of the take-up package upon failure of thread, tubes and bobbins may be exchanged and threads spliced on one set of a plurality of twisting mechanisms of the device without interfering with the remaining sets of the 15 device. To still further increase the number of packages that one operator can maintain in running condition there is need of a quick yet positive means of removing a completely filled package and inserting an empty package core or tube. 20 This desired result is accomplished according to this invention by means of an expansible tube holder as shown in detail in Figs. 2 through 5 on the drawings.

A suitable bracket 53 for supporting a tube 22 25 is provided having means for raising same on failure of thread or by the operator when a complete package has been formed on the tube. This bracket may be of any suitable construction but for the particular device shown in Fig. 1 it may 30 consist of a bracket body 53 having a U shaped portion, the ends of which are split bearings 57 adapted to be mounted for pivotal movement about a stationary rod 54, and an arm 111 for supporting an expanding tube holder 110. Arms 57 35 are drilled for rod 54 and slotted in an approved manner at 112 to provide a spring action about the rod 54. The spring action of the arms 57 may be governed by screws 56. Screws 56 are preferably long enough for a suitable compression 40 spring 101 to be placed under its head for forming a resilient adjustment for arms 57. The more pressure applied to stationary rod 54 by bearing arms 57 causes the bracket 53 to pivot about the rod with a more determined action. 45

In operation, tube 22 when the operation has first started, or yarn or thread 55 when the operation or winding process has advanced so that yarn substantially covers tube 22, comes in contact with the friction or cork covered roll 23 or 50 we may say lies on cork roll 23. The lie of the take-up package on roll 23 is governed by the amount of adjustment made to bracket arms 57 by cap screws 56. The tighter the adjustment 55 the more steady and/or fixed will the package lie on the friction roll 23, eliminating what is known as "dancing" or "jumping" of the package.

The U shaped bracket may be provided with an extended arm 111 having a split bearing controlled by the clamping screw 103. This bearing 60 is adapted to hold a nonrotating shaft 102. The U shaped bracket may also be rounded where it engages 52 for more sure registry with the lifting means. 65

The shaft 102 is provided with a suitable male right hand buttress or other fast-feed screw thread 114 on which is threaded, by means of a similar female thread 113, an actuating thrust collar 104. The buttress thread is preferably reversed so as to provide a self-locking action when tightened. 70

An expanding tube holder 110, is counterbored at each end, leaving an inclined shoulder 119, and is slotted along the length of the tube with slots 75

118 about its circumference. Expanding tube holder 110 is also provided with an external shoulder 120 at one end that acts as a stop when placing in position the tube or core 22 on which 5 the thread or yarn is to be cross-wound.

Thimble 105 which is suitably formed to receive radial thrust bearings 106 and thrust collar 104 and thimble 121' which suitably formed to receive radial thrust bearings 106 and retainer collar 107 10 are placed one in each end of the expanding holder 110. This assembly is placed on shaft 102. The retainer collar 107 may be held in place in the assembled device by means of a left hand threaded cap screw 108. The purpose of using 15 a left hand thread on 108 is to insure that the retainer collar 107 shall always be held tightly in place, since the direction of rotation of the assembly is left handed when viewed from the outer end of the shaft 102. Other locking means 20 may however be employed.

Thrust collar 104, is provided with a suitable handle 109. Thrust collar 104, retainer collar 107, and thimbles 105 and 121', may also be provided with suitable oil grooves and washers to prevent 25 throwing of lubricating oil. Thimbles 105 and 121' are so constructed so that they will ride freely and easily along inclined surface or shoulders 119 of expanding holder 110.

In operation, handle 109 is raised to position 30 shown in dotted lines in Fig. 3, and when in this position there is no expansion of tube holder 110. The tube or core 22 may be freely slid on or off the holder. In loading, a tube or core 22 is placed in position on holder 110 and against the 35 stop shoulder 120'. Handle 109 is then moved to the position shown in full lines in Fig. 3 which causes the actuating thrust collar 104 to rotate about shaft 102 through buttress threads 114 and 113 in a direction that will force it against the 40 bearing 106. Thimble 105 being forced inwardly of the holder, by action or feed of the buttress threads 114 and 113 through bearing 106 causes an opposite and equal pressure on thimble 121' through expanding holder 110, since thimble 121', 45 its bearing 106 and retainer collar 107 are held in an axial stationary position by cap screw 108. The action of thimble 105 moving inwardly and exerting pressure to thimble 121' through expanding holder 110 causes expanding holder 110 to expand in a radial direction. This expansion 50 grips the tube or core 22 and holds it in place during the winding operation.

At the completion of the winding operation, the handle 109 is again moved to dotted line position, 55 which causes, through buttress threads 113 and 114 acting on collar 104 and shaft 102 respectively, to relieve the pressure on the bearings 106, and on the thimbles 105 and 121'. This pressure being relieved, and the expanding tube 60 holder not having been forced past its elastic limit, resumes its original shape and in so doing forces the thimbles 105 and 121' apart. The internal pressure on the tube or core 22 is then released and the completed cheese or other package 65 55 may be removed.

In a modified form of my device as shown in Figs. 6 through 8 there is employed a simple form of drive for imparting a variable reciprocation to the thread guides 21. This drive device is adapted 70 for use on automatic twisting devices and especially on the type shown in Fig. 1. In the drawings, with particular reference to Figs. 1 and 6 there is shown a shaft 31—33 upon which is mounted a friction roll 23, that supports and turns 75 a take-up package 55. The shaft 33 is driven

from a suitable source of power through gears 25, 26, 28 and 29 (see Fig. 1).

On shaft 33 is fastened a sprocket wheel 64. Suitably journaled in the main frame is a shaft 116 lying parallel to and beneath shaft 33 having 5 fastened thereto a sprocket wheel 117 that registers with and is driven from sprocket wheel 64 by a sprocket chain 118 imparting a positive movement to shaft 116 in timed relation to the peripheral speed of the take-up package 55. 10

Fastened on shaft 116 by means of a key 119 or other suitable means are two gears 120 and 121. Gear 120 is slightly larger than gear 121.

A shaft 88 suitably journaled in a drum cam box 95 that is a part of the main frame has fastened thereto a drum cam 87. The shaft 88 has mounted thereon and rotatable with respect thereto two gears 122 and 123 that register with and are driven from gears 121 and 120 respectively. The diameter of gear 123 is less 20 than the diameter of gear 122 so that in registering with gears 120 and 121 the shafts 116 and 88 may be substantially parallel.

Fastened to or made a part of gear 122 is an elliptical gear 124 eccentrically pivoted on shaft 25 88. Gear 123 is formed with a bearing member 125 in which is mounted a shaft 126 adapted to rotate therein. The shaft 126 has fastened thereto as by a key 127 or made integral therewith an elliptical gear 128 mounted eccentrically of shaft 30 126 and in registry and driving relation to elliptical gear 124. On the opposite end of shaft 126 is a gear 129 fastened thereto by means of a key or other suitable means.

Keyed to, or otherwise suitably fastened in 35 driving relation to shaft 88 is a gear 130 that registers with and is in driving relation to gear 129 on shaft 126. The gear 130 is keyed to or otherwise fastened to shaft 88 and imparts rotation thereto which in turn rotates drum cam 87. On 40 drum cam 87 there is two cam ways 92 and 93 in the latter of which a roller pin 91 is adapted to be guided. Pin 91 is suitably fastened to a slide head 90 that is fastened by adjustable rod 96 to the reciprocating thread guide holder rod 89. 45

The action of the drive mechanism is as follows: Shaft 116 is driven by a suitable gear wheel or chain from the friction roller drive shaft 33. The two gear wheels 122 and 123 then rotate at slightly different speeds so that there is a relative motion between them to give one relative revolution for each complete cycle of traverse variation. The major and minor axes of the elliptical wheels may be chosen to give the required variation of traverse on either side of the mean speed. 55 The elliptical wheel 128 will make one revolution for each revolution of the wheel 122 relative to the wheel 123. Since the wheels 128 and 129 are both positively fastened to the same shaft, it follows that the wheel 130 must make one revolution relative to the wheel 123 for each relative revolution of the wheel 122, but since the wheel 130 gets this motion through the elliptical pair of wheels, its speed will not be uniform. The net result is to superimpose a variable velocity on to 60 the uniform velocity of revolution transmitted to the wheel 123. The mean velocity of revolution of the shaft 88 and the cam drum 87 will be the same as that of the wheel 122, but there will be a slow relative backward and forward movement of the shaft 88 with relation to the wheel 123. 65

Obviously many additions and alterations may be made in the disclosed device without departing from our invention. For example a device 75

- may be inserted between eyelets 19, or at another suitable point for treating the twisting yarn with lubricants, sizes, plasticizers or other treating liquids, gases or solids. Further the complete 5 assembly may be of any desired size and contain any suitable number of sets or units that may be spaced along one or both sides of the assembly. The height of the device and thus shaft 24 may be any suitable height to compensate for size of 10 balloon formed and auxiliary treating elements attached. Guides 19 may be adjustable as by permitted, regulated movement of the bars to which they are attached. Other like modifications may be made.
- 15 It is to be understood that the foregoing detailed description and drawings are merely given by way of illustration and many alterations may be made therein without departing from the spirit of our invention.
- 20 Having described our invention what we desire to secure by Letters Patent is:
1. In a device for unwinding yarn from a bobbin and rewinding the same onto a take-up package, wherein the bobbin is mounted on a spindle 25 driven by a rotating member and the take-up package is rotated by a friction drum, the combination with a drop wire normally held in raised position by the yarn being wound, of a lifting rod having a spring thereon, means for holding said 0 lifting rod depressed against the action of the spring and means for releasing said holding means, said releasing means including a member adapted to reciprocate out of contact with

said holding means and adapted upon breakage or failure of the yarn to be raised, by the fall of the drop wire, into operative position for releasing the lifting rod holding means, the construction and arrangement being such that the 5 released lifting rod operates to simultaneously remove the spindle from contact with said rotating member and the take-up package from contact with said friction drum.

2. In a device for unwinding yarn from a bobbin and rewinding the same onto a take-up package, wherein the bobbin is mounted on a spindle driven by a rotating member and the take-up package is rotated by a friction drum, the combination with a drop wire normally held in raised 10 position by the yarn being wound, of a lifting rod having a spring thereon, means including a trigger for holding said lifting rod depressed against the action of the spring and means for releasing said holding means, said releasing means including a lug-carrying member adapted to reciprocate out of contact with said holding means and adapted upon breakage or failure of the yarn to be raised, by the fall of the drop wire, into a position wherein the lug contacts with the trigger 15 to release the lifting rod, the construction and arrangement being such that the released lifting rod operates to simultaneously remove the spindle 20 from contact with said rotating member and the take-up package from contact with said friction 25 drum.
